UNITED STATES PATENT OFFICE.

JAMES M. JORDAN, OF CHURCHVILLE, VIRGINIA.

ELECTRIC GRAIN-HEATER.

1,189,575.

Specification of Letters Patent.

Patented July 4, 1916.

Application filed August 5, 1915. Serial No. 43,830.

To all whom it may concern:

Be it known that I, JAMES M. JORDAN, a citizen of the United States, residing at Churchville, in the county of Augusta and 5 State of Virginia, have invented a new and useful Electric Grain-Heater, of which the following is a specification.

This invention relates to electric grain heaters, one of the objects thereof being to 10 provide a simple, compact and efficient drier especially designed to use an electric heater 15 so that the same can be used efficiently in mills run by water power and where steam, which is commonly employed in grain driers, is not ordinarily available.

A further object is to provide a grain drier or heater having means of novel form for distributing the grain into separate streams which, as fed past the heater, will 20 be thoroughly dried before being discharged into the mill.

Another object is to provide simple means for retarding the flow of the grain through the drier, said means also constituting a 25 discharge spout whereby the grain is directed into the mill.

Another object is to provide a drier the parts of which can be assembled readily and can be easily taken apart for the purpose of 30 repairing or replacing any of the parts.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without 40 departing from the spirit of the invention.

In the accompanying drawings the preferred form of the invention has been shown.

In said drawings: Figure 1 is a central 45 vertical section through the drier, the spreader and the heater being shown in elevation. Fig. 2 is a top plan view of the drier with the top section removed. Fig. 3 is a section on line A—B Fig. 1.

50 Referring to the figures by characters of reference 1 designates a drum having a concentric metal lining 2 and between this lining and the wall of the drum is packed an insulating material 3 which can be of asbestos or the like. The lining 2 and the insulating material 3 do not extend up to the

upper end of the drum 1 but terminate a short distance therebelow so as to form a ledge adapted to support the peripheral portion of a disk 4. Rods 5 extend downwardly 60 from this disk at points adjacent the lining 2 and are held to the disk by nuts 6 engaging the upper and lower faces of the disk. The lower ends of the rods are similarly secured to a bottom disk 7 which fits snugly 65 within the lower portion of the lining 2.

Mounted upon the disk 4 and concentric therewith is a spreader 8 preferably bell-shape and which is held to the disk 4 by a bolt 9 extending downwardly through the 70 spreader and through the center of the disk, said bolt being held by a nut 10 or in any other desired manner. A series of closely disposed openings 11 is formed within the disk 4 and extends around the spreader 8, 75 these openings lying between the spreader and the rods 5. A similar arrangement of openings 12 is provided in the lower disk 7. Arranged within the openings 11 and 12 are tubes 13 the upper ends of which are formed 80 with annular flanges 14 adapted to bear downwardly on the disk 4 and thus hold the tubes suspended within the openings 11 and 12. The lower ends of the tubes are disposed close to but below the disk 7.

The series of tubes 13 and the disks 4 and 7 define a central heating chamber 15 in which is arranged an electric heater 16 of the usual or any preferred form, this heater being secured to the middle portion of the disk 90 7 so as to stand rigidly within the heating chamber. A flat tubular stem 17 is secured to the bottom of the disk 4 and extends outwardly therebeyond to a socket 18 to which cords 19 are adapted to be connected electrically. The tubular stem 17 has electric 95 conductors therein from which extend wires 20 leading to the heater 16. A short longitudinal slot 21 is formed in the upper end of the drum 1 and its lining, this slot being 100 designed to receive the stem 11. Thus it will be seen that when the parts are assembled, the socket 18 will be supported beyond the drum 1, while the spreader 8, the tubes 13 and the other parts hereinbefore described will be housed within the drum.

However, said parts can be removed readily from the drum simply by lifting them so as to remove the disk 4 from the upper end of the lining 2 and to withdraw the stem 17 105 from the slot 21.

Removably engaging the upper end of the

drum 1 is a cylindrical inlet section 22 having a frusto-conical upper portion 23 from which extends a feed tube 24. This feed tube is located directly above the spreader 8 so that material when discharged through the tube and into the section 22 will fall directly onto the spreader and be distributed to the several tubes 13. Extending inwardly and downwardly from the wall of the section 22 5 is a frusto-conical deflector 25 which cooperates with the spreader 8 to form an annular channel from the bottom of which extend the tubes 13. Consequently, material directed into the section 22 will not only be 10 deflected by the spreader 8 toward the tubes 13, but would also be deflected toward said tubes by the deflector 25. Thus no corners or shoulders will be left upon which grain might accumulate and thus clog the working 15 of the drier. Detachably connected to the lower end of the drum 1 is a cylindrical bottom section 26 having a frusto-conical downwardly extending portion 27 from which projects an outlet tube 28, the diameter of 20 this tube being less than that of the tube 24. 25

It will be noted that the tubes 13 converge downwardly to a slight extent so that the grain, in descending through the tubes will slide or roll along the walls of the tubes and 30 not fall directly through the tubes as would be the case should the tubes be vertical.

In using the drier, current is directed to the heater 16 with the result that the temperature of the tubes 13 is raised to a desired degree. The grain to be dried is then directed through tube 24 into section 22 and will be deflected to the tubes 13 by the spreader 8 and deflector 25. While passing 35 through the tubes the grain will be dried, and the dried grain will be discharged into the section 26 from which it will pass by way of the tube 28. As the diameter of the tube 28 is less than the inlet tube 24, it will be apparent that the grain cannot 40 escape from the drier as fast as it is supplied thereto. Consequently the grain will be retarded in its passage through the drier so that the complete drying of the grain will be insured before said grain is discharged 45 from the drier.

What is claimed is:—

1. A grain heater including a drum, an insulated lining therein forming a supporting ledge at its upper end, a top disk supported 55 upon the ledge, a bottom disk within the lower portion of the drum, connections between the disks, a circular series of tubes extending through the disks and forming a

heating chamber therebetween, a spreader upon the top disk and between the upper 6 ends of the tubes, means for directing grain onto the spreader and into the tubes, and a heater within the heating chamber.

2. A grain heater including a drum, an insulated lining therein forming a ledge at its 6 upper end, a top disk supported at its periphery upon said ledge, a bottom disk, tubes extending through the disks and forming a heating chamber therebetween, a heater within said chamber, an inlet section removably mounted upon the upper end of the 7 drum and having a feed tube opening thereto, a spreader upon the upper disk and below the feed tube and between the upper 7 ends of the tubes in the disks, a bottom section detachably engaging the drum, and an outlet tube extending from the bottom section, said outlet tube being of less diameter than the feed tube.

3. A grain heater including a drum, a lining therein forming a ledge at its upper end, a top disk supported on the ledge, a bottom disk within the drum, detachable connections between the disks and within the drum, a circular series of tubes extending through 8 the disks and converging downwardly, a spreader upon the top disk and between the upper ends of the tubes, a heating medium surrounded by the tubes, an inlet section detachably engaging the upper end of the 9 drum, a downwardly and inwardly inclined deflector carried by said section and terminating close to the tubes, a feed tube opening into the inlet section and above the deflector, a bottom section detachably engaging 9 the drum, and an outlet tube extending therefrom and of less diameter than the feed tube.

4. A grain heater including a drum, an insulated lining therein, a top disk supported in the drum, a bottom disk within the lower portion of the drum, connections between the disks, a circular series of tubes extending through the disks and forming a heating chamber therebetween, a spreader 10 upon the top disk and between the upper ends of the tubes, means for directing grain onto the spreader and into the tubes, and a heater within the heating chamber.

In testimony that I claim the foregoing as 11 my own, I have hereto affixed my signature in the presence of two witnesses.

JAMES M. JORDAN.
